HYDRAULIC JACK

Joseph J. Mueller, St. Joseph, Mich., assignor to
 Auto Specialties Manufacturing Company, St.
 Joseph, Mich., a corporation of Michigan

Application May 13, 1944, Serial No. 535,436

12 Claims. (Cl. 60—52)

1

This invention relates to hydraulically operated pushing and pulling devices, and more particularly to hydraulic jacks for lifting relatively heavy loads.

Among the objects of the present invention are to provide an hydraulic jack that is composed of a minimum number of parts, each of simple construction, the parts being designed to be capable of economical and ready manufacture and easily assemblable into an operable hydraulically operated jack structure.

Further objects of the invention are to provide an hydraulic jack including a base suitably formed to provide a ram cylinder and a surrounding reservoir and provided with but one additional bore extending to the exterior of the base for the purpose of receiving a combined high pressure pump cylinder and release valve, the jack including mechanism for reciprocating the piston of the pump in the pump cylinder and for longitudinally sliding, without turning, the high pressure pump cylinder for the purpose of closing the release valve upon its seat, the closing mechanism being constructed and arranged so that upon release movement thereof the high pressure pump cylinder will be released for shiftable movement in a reverse direction, whereby the pressure in the ram cylinder will effect an unseating movement of the release valve to relieve the liquid from the ram cylinder back into the reservoir; to provide a simple and economical manner of forming a combined high pressure pump cylinder with its reciprocable piston, together with a valve cage unit and release valve operable as a unit and shiftable without turning, parallel to its own longitudinal axis and wherein the piston is capable of easy pivotal connection to the piston reciprocating mechanism, and wherein the cylinder is capable of easy connection to mechanism pivoted on the base for sliding the cylinder, the valve cage and the release valve relatively to a valve seat formed in the base for controlling the relief of the ram cylinder; to provide these and other objects of invention, as will be apparent from the following specification when taken in connection with the accompanying drawings, wherein:

Figure 1 is a front elevation of one form of my improved jack;

Figure 2 is a side elevation thereof;

Figure 3 is a plan view thereof;

Figure 4 is a section on the line 4—4 of Figure 2;

Figure 5 is a perspective view of the high pressure pump cylinder piston, ball valve cage unit,

2

and release valve, with the connection to the shifting mechanism therefor;

Figure 6 is a detail fragmentary sectional view showing the valve cage and release valve shifted to closed position on its seat; and

Figure 7 is a section taken on the line 7—7 of Figure 6.

Referring now to the drawings in detail, the jack preferably comprises a base 2 herein shown 10 as formed with a well 4 having upstanding, internally threaded walls 6 concentrically surrounding the well and adapted to receive the lower, externally threaded ends of the ram cylinder 8. In addition, the base 2 is provided with a 15 concentrically surrounding shouldered and countersunk portion 10 which receives an additional sleeve 12 forming the liquid reservoir 14 between it and the cylinder 8. The junction between the shoulder 10 and the lower portion 20 of the sleeve 12 is a press fit which is in addition welded so as to form a very secure union.

A head 16 forms a welded press fit junction 18 with the outer sleeve 12 and in addition the inner wall of this head is threaded as at 20 to 25 receive the threaded external walls of the ram cylinder 8. The inner annular surface 22 of the head is cored out or cut out as at 22 to provide an oil chamber and the usual type of packing 24, and the usual threaded washer 26 is threadedly 30 connected to the top of the head 16 to hold the packing in position so that the ram 28 may reciprocate through the packing without leakage of oil thereby. The upper end of the ram is provided with the load support 30, and the lower end 35 of the ram is provided with the usual sealing ring 32 formed of leather or other flexible material and held in place by means of the usual fastening member 34, as is well known in the art.

40 The base is provided with one additional boring or opening which extends to the exterior of the base, and this comprises the bore 36 which receives the high pressure pump cylinder, the piston reciprocable therein, the unitary ball valve 45 cage and release valve. No other conduit formed in the base extends to the exterior of the base, thereby keeping leakage to a minimum. The basal casting is provided with a conduit 38 which connects with the well 4. This passage 38 is 50 formed in the base 2 at such an angularity that its projection passes above the upper surfaces of the base so that when the ram cylinder 8 and reservoir cylinder wall 12 are removed from the base, the conduit 38 may be bored from the upper 55 face of the base. The outer end of this conduit

connects with another short conduit 40, the center of which registers with the central axis of the bore 36. This conduit 40 is cut away to provide a conical wall 42 to provide an abrupt annular shoulder 43 forming a release valve seat of minimum cross section and which valve seat communicates with the laterally extending axial bore or conduit 38. This valve seat is for the purpose of connecting conduit 44 leading to the reservoir, to the conduit 38 leading to the ram cylinder, when the release valve is raised from its seat. It will thus be seen that the bore 44 and the valve seat 43 all connect with the bottom of the bore 36.

The basal casting at one side of the cylinder 12 is provided with an upstanding projection 46 about the bore 36, and this projection 46 is provided with an opening 50 to receive a pivotal pin 52 as hereinafter described.

The high pressure pump cylinder is formed in a novel manner. It is formed of a short length of steel tubing, preferably formed by cutting a long steel tube into requisite lengths to correspond with the length of the high pressure pump cylinder desired. The steel tubing is given a high finish interiorly, preferably before it is cut into lengths, so that no further interior finish need be imparted to the high pressure pump cylinder, which will reciprocatingly receive the high pressure pump piston without further finishing operation. Thus the high pressure pump cylinder 54 is formed in an appropriate length of steel tubing, as shown in Figure 5. It is round in cross section and receives, with a tight fit at its upper end, an annular ring or head 56 which ring is closed at both ends, one of the ends receiving a threaded nut 58 to press a packing 61 within the annulus tightly against the piston 62 which is adapted to reciprocate through the sleeve-like cylinder 54 and head 56. The head is preferably provided with two outstanding diametrically opposed studs 60, and this head is adapted to make a tight wedging or welded fit with the upper end of the outer surface of the sleeve 54 while reciprocatingly receiving the piston 62 therethrough. The outer end of the piston is provided with a slot 64 to receive in the usual manner the connecting pin 66 connected by a yoke 68 to the handle bar 70 which receives the reciprocable handle bar 72. The inner end of this handle socket 70 is pivoted as at 74 to an outstanding ear 76 formed on the sleeve 12. The inner end of the handle bar 72 is notched as at 78 to engage the valve shifting mechanism, as hereinafter set forth.

The lower part of the piston is provided with the usual sealing washer 80, as is well known in the art, the same being held in position by means of the screw 82.

The extreme lower end of the high pressure pump cylinder 54 makes a tight fit with a countersunk shoulder 86 formed on a unitary ball valve cage, the details of which are shown more clearly in Figure 6. This ball valve cage comprises a ported member or ported means having internal valves governing passages which are adapted to connect the passage 44 leading to the reservoir with the piston chamber within the cylinder 54 so that when the piston moves outwardly, liquid will be drawn through the port 44 into the port 88, thence into port 90, past ball valve 92, into the piston chamber 94. Upon reverse movement of the piston, liquid will be forced through the port 96 past the ball valve 98, through port 100, through port 103, into port

40, thence through passage 38 to the ram cylinder. The balls are held close to their seat by means of inserted wires 102.

The lower end of the ball valve cage is preferably provided as a separate hard metal cap or valve member 101 having a central port 103 therethrough and provided with abruptly shaped conical walls 104 of such angularity as to seat upon the annular shouldered valve seat 43 with a minimum annular contact, whereby a tighter seating of the valve upon the valve seat is provided, and thus closing any direct connection between the ports 38, 40 and 44 while permitting liquid to flow through the ball valve cage, through the reservoir to the pump cylinder chamber, to the ram cylinder. This member 101 to this end is provided with a countersunk shoulder the upper portion of which fits within a recess countersunk within the end of the ball valve cage and the fit is such that the upper face 115 of this release valve 101 is sufficiently close to ball 98 to hold it upon its seat. In addition, the ball valve cage at the opening at which the ball valve 92 operates, is peened in as shown at 107 to hold the ball in position relative to its seat. Means is provided for manually shifting the combined structure shown in Figure 5 which comprises the high pressure pump cylinder which rigidly carries the ball valve cage 87 and the release valve 104 therewith, to force the release valve 104 to its seat 43. This means comprises mechanism which, without turning or permitting the turning of the high pressure pump cylinder, shifts this high pressure pump cylinder, ball valve cage, and release valve in a direction parallel to the longitudinal axis of this structure so as positively to draw the release valve to its seat. In addition the structure is arranged so that upon a release movement, the liquid pressure which has been built up in the ram cylinder during the raising of the ram, will automatically force this structure, which includes the release valve, from its seat and thereby relieve the ram cylinder pressure so that liquid will flow from the ram cylinder at well 4 through the ports 38 and 40 through the open release valve, through port 44, back to the reservoir. This means comprises a linkage mechanism which includes a type of bell crank lever 106 pivoted about the fixed pivot 52. This lever includes an arm 108 internally threaded at 110 to receive the screw 112, the screw having at its inner end a rounded surface 113 and at its outer end the cross bars 116 by which it may be turned when contacted by the notch 78 in the inner end of the handle 72. In addition the other end of the bell crank 106 includes the forks 114, there being two of them which are pivoted as at 117 and 118 to a pair of links 120 and 122 which in turn are pivoted to the opposed, diametrical pins 60 outstanding from the head 56. The arrangement is such that when the outer ends 116 of the screw 112 are turned in the correct direction, the bell crank will shift about its fixed pivot whereby to draw down upon the links 120 and cause the head 56 to be drawn down whereby to likewise shift the high pressure pump cylinder 54 downwardly, thereby shifting the unitary ball valve cage and release valve formed now integrally with the lower portion of the pump cylinder, downwardly, to close the release valve upon its valve seat 43. When the screw 112 is turned in the reverse direction it will release this drawing down action so that the pressure built up in the conduit 38 and 40 will now force the unitary structure 54, 87, and 104 outwardly away

from the seat to relieve the ram cylinder pressure. It will be noted that this movement of the high pressure pump cylinder is independent of any reciprocable action of the piston 62 in the pump cylinder and is therefore independent of any reciprocable position of the piston in the pump cylinder.

By the foregoing mechanism I provide a very simple, economical, rugged jack, which is composed of few parts, easily manufactured, easily and quickly assembled into a completely operative structure wherein the release valve may be opened or closed from a point readily accessible on the jack and without any involved interrelation with the reciprocable piston, and particularly by means of the present construction I have reduced to a minimum number of parts the mechanism for shifting the high pressure pump cylinder relatively to the base of the jack for accomplishing the shifting of the release valve onto its seat and conversely for permitting the pressure in the ram cylinder to shift the release valve from its seat automatically. In addition, it will be seen that I have provided a simple means for manufacturing a high pressure pump cylinder from steel tubing, completely finished within so as to receive the high pressure pump piston without further finishing operation, and I have provided means whereby the jack may be readily taken apart to repair any defective operation of the ball valves. This repair work is accomplished in a very simple manner by disconnecting the operating mechanism from the high pressure pump piston, removing it and the cylinder from the base, so that the ball valve cage and release valve are exposed. If desired, the ball valve cage is readily removed from the lower end of the high pressure pump cylinder for repair or replacement.

Obviously the invention is not limited to the specific details of construction disclosed herein but is capable of other modifications and changes without departing from the spirit and scope of the appended claims.

Having thus described my invention, what I claim as new and desire to secure by Letters Patent is:

1. In an hydraulic jack having a base provided with a bore, said base having thereon a ram cylinder, a liquid reservoir associated with said base, a pump cylinder comprising a sleeve of uniform cross section having a smooth exterior slidable in said bore, a ram in the ram cylinder, a piston reciprocable in the pump cylinder sleeve, conduit means in the base interconnecting the reservoir, the pump cylinder and the ram cylinder, ported and valved means carried by said pump cylinder sleeve for transferring liquid through said conduit means from the reservoir to the pump cylinder, and from the pump cylinder to the ram cylinder upon reciprocation of said piston, release valve means including a valve seat formed in the base in association with certain of said ports and including a release valve carried by said ported and valved means and shiftable with said cylinder sleeve and ported and valved means, and means connected with said cylinder and operative from a point exteriorly of said base, for sliding said sleeve in a direction parallel to its longitudinal axis while holding said sleeve from rotation for closing said release valve upon its seat.

2. In an hydraulic jack, a base having a ram cylinder, a liquid reservoir and a pump cylinder bore, a ram in the ram cylinder and a pump

cylinder slidable in said bore and a reciprocable piston in the pump cylinder, conduit means interconnecting the reservoir, the pump cylinder and the ram cylinder, ported and valved means carried by said pump cylinder for transferring liquid through said conduit means from the reservoir to the pump cylinder, and from the pump cylinder to the ram cylinder upon reciprocation of said piston, release valve means including a valve seat formed in the base in association with certain of said ports and including a release valve carried by said ported and valved means and shiftable in said bore with said cylinder, and linkage means pivoted to said base and to said pump cylinder and operable from the exterior of said base for sliding said cylinder longitudinally to close said release valve upon its seat.

3. In an hydraulic jack having a base provided with a bore, a ram cylinder, a liquid reservoir associated with said base, a pump cylinder slidable in said bore, a ram in the ram cylinder and a reciprocable piston in the pump cylinder, conduit means interconnecting the reservoir, the pump cylinder and the ram cylinder, ported and valved means carried by said pump cylinder for transferring liquid through said conduit means from the reservoir to the pump cylinder, and from the pump cylinder to the ram cylinder upon reciprocation of said piston, release valve means including a valve seat formed in the base in association with certain of said ports and including a release valve carried by said ported and valved means and shiftable with said pump cylinder, an annular head mounted on the outer part of said pump cylinder and through which said piston is adapted to reciprocate, and linkage means pivotally mounted on said base and connected with said head and operable exteriorly of said base for sliding said pump cylinder parallel to its longitudinal axis for closing said release valve upon its seat.

4. In an hydraulic jack having a ram cylinder, a liquid reservoir and a pump cylinder in the form of an elongated sleeve, a ram in the ram cylinder and a reciprocable piston in the pump cylinder, conduit means interconnecting the reservoir, the pump cylinder and the ram cylinder, ported and valved means carried by said pump cylinder sleeve for transferring liquid through said conduit means from the reservoir to the pump cylinder, and from the pump cylinder to the ram cylinder upon reciprocation of said piston, release valve means including a valve seat formed in the base in association with certain of said ports said by-pass valve means including a valve carried by said ported and valved means and shiftable with said pump cylinder sleeve, and an annular head exteriorly mounted on the opposite end of said sleeve and through which said piston is adapted to reciprocate as said piston reciprocates in said pump cylinder sleeve, a piston actuator pivotally mounted on said jack and connected to the outer end of said piston, and means mounted on said jack and connected to said head for shifting said pump cylinder sleeve in a direction parallel to its longitudinal axis while holding said pump cylinder sleeve from rotation for closing said release valve upon its seat.

5. An hydraulic jack comprising a base having liquid passages therein, means providing a ram cylinder and a liquid reservoir for said base, a ram in said ram cylinder, said base having a bore formed with an enlargement at its mouth in the upper part of the base, a pump cylinder in the form of an elongated sleeve mounted in

said bore and projecting beyond said base, packing means in the enlargement of said bore exteriorly of said sleeve, means connected with the base around said bore enlargement for holding said packing means compressed against said cylindrical pump sleeve while permitting movement of said cylindrical pump sleeve parallel to its longitudinal axis, a pump piston reciprocal in said pump cylinder sleeve, said base at the central portion of the bottom of said bore being provided with a valve seat in association with certain of said liquid passages of said base, a ported valve cage disposed in said bore and located between said valve seat and the end of said pump sleeve, the lower portion of said cage being formed as a release valve to close upon said valve seat, an annular head connected to the outer end of said pump cylinder sleeve and through which said pump piston is adapted to reciprocate as it reciprocates in said cylindrical pump sleeve, packing means in said head about said piston, means for compressing said packing means between said head and said piston, a piston actuator pivotally mounted on said jack and pivotally connected to the outer end of said piston, and linkage means pivotally connected with said head and pivotally mounted on said jack for shifting said pump cylinder sleeve in a direction parallel to its longitudinal axis while holding it from turning.

6. A high pressure pump cylinder and release valve assembly for hydraulic jacks comprising an elongated metallic cylindrical sleeve of uniform cross section or diameter throughout its length, the inner wall of said sleeve having a polished metal finish, a separate cylindrical cage telescopically fitting into one end of said sleeve, said cage having at least two ports therethrough, one of said ports opening onto opposite ends of said cage and the other port opening onto one end of the cage and also onto the circular periphery of said cage, valves in said cage for controlling said ports, said cage having a conically shaped nose attached to its free end, said nose having a port disposed centrally of the conically shaped outer walls of said nose, said port connecting the outer end of said nose with one of said passageways in said cage, the outer walls of said cage and nose lying wholly within the peripheral or outer plane of said cylindrical sleeve, the outer wall of said cylindrical sleeve being smooth from the end carrying said cage for the major portion of the length of said sleeve to provide a sliding surface to slide in a bore in the jack.

7. An hydraulic jack comprising a relatively low basal casting having a centrally disposed well and a concentrically surrounding shoulder portion around said well, said shoulder portion being internally threaded, the upper portion of said base concentrically about said threaded portion being provided with a laterally extending wall and an upper shoulder providing a second horizontally extending wall and a third upstanding shoulder, a cylindrical tube externally threaded and engaging the internal threads of said threaded portion surrounding said well to provide a ram cylinder, a ram in said cylinder, a sleeve having its lower end seated upon the horizontal portion just within said last mentioned shoulder and press fitted and welded thereto to form a reservoir, a head interconnecting the outer ends of said tube and sleeve to close said reservoir at the top, said head having a passage to permit the projection of said ram therethrough, said base having a bore extending at an angle to the central longitudinal axis of said ram cylinder, the bottom of said bore being

formed as a valve seat, said valve seat having a centrally disposed conduit therein formed concentrically with the axis of said bore, said base having formed therein a passage connecting the reservoir with said bore, a pump cylinder slidably in said bore, a combined ported and valved unit in the bottom of said bore and operably carried by said pump cylinder, the lower portion of said unit being formed as a release valve to close upon said seat, a piston slidable in said pump cylinder, means for operating said piston, means for sliding said pump cylinder parallel to its longitudinal axis, and a port formed in said base connecting said well with the port formed concentrically at the axis of said valve seat, a geometric projection of the walls of said last named port passes above the topmost portions of said basal casting whereby before said cylinder is assembled on said basal casting said last named port can be drilled from the top of said base diametrically through said well into said port that lies along the central axis of said bore in said base.

8. An hydraulic jack comprising in combination a base, concentric ram and ram cylinder means upstanding from said base, means on said base providing a reservoir, said base having a pump cylinder bore provided at its bottom with a release valve seat, conduits formed in said base interconnecting said pump cylinder bore, said release valve seat, said ram cylinder, and said reservoir, a high pressure pump cylinder sleeve slidably in said pump cylinder bore and having an outer portion projecting beyond the exterior wall of said base, an actuator rigidly connected to that portion of said pump cylinder sleeve which projects outside of said bore, said pump cylinder sleeve having an inner end portion the walls of which form a release valve to close upon said release valve seat, said inner end portion of said pump cylinder sleeve having an internal liquid passage therethrough connecting with the interior of said pump cylinder sleeve, valve means controlling said passage to permit liquid to flow therethrough only from said pump cylinder to said ram cylinder, said end portion having a second conduit connecting the interior of said pump cylinder with said reservoir, valve means allowing liquid to flow through said second conduit only from said reservoir to said pump cylinder, a piston reciprocable in said pump cylinder sleeve, an actuator for said piston, and means for imparting rectilinear movement to said actuator to cause it to slide said pump cylinder sleeve in the bore of said base to position said release valve carried by said cylinder onto its seat.

9. An hydraulic jack comprising in combination a base, concentric ram and ram cylinder means upstanding from the base, means associated with said base providing a reservoir, said base having a pump cylinder bore, said bore adjacent the bottom portion thereof being formed with a release valve seat and a connected passageway connecting with the ram cylinder, said bore likewise having a passageway connecting with the reservoir, a high pressure pump cylinder slidably mounted in said bore and being provided on its lower end with walls forming a release valve that are adapted to seat upon and close off the release valve seat, said pump cylinder being formed above said release valve portion with a port one end of which is constantly in communication with the passageway leading to the reservoir and the other end of which passageway leads to the interior of the pump cylinder, said last men-

tioned passageway having a valve seat therein and a valve for closing upon said seat in a manner to permit liquid to pass from said reservoir through said passageway to within the pump cylinder, but not reversely, said pump cylinder having another liquid passageway therethrough adapted to connect the interior of the pump cylinder with the passage in the base leading to the ram cylinder, a valve seat in said last mentioned passageway and a valve for allowing liquid to pass from said pump cylinder through said passageway to said ram cylinder, but not reversely, a piston reciprocable in said pump cylinder, said pump cylinder projecting outwardly of said bore beyond the exterior walls of said base, an actuator rigidly connected to that part of the pump cylinder projecting beyond said base, and means for moving said actuator to slide said pump cylinder inwardly relatively to said base to seat the release valve upon the valve seat.

10. An hydraulic jack comprising in combination a base, concentric ram and ram cylinder means upstanding from the base, means associated with said base providing a reservoir, said base having a pump cylinder bore, said bore adjacent the bottom portion thereof being formed with a release valve seat and a connected passageway connecting with the ram cylinder said bore likewise having a passageway connecting with the reservoir, a high pressure pump cylinder comprising an elongated sleeve having a smooth outer wall, said sleeve being slidably mounted in said pump bore, a piston reciprocable in said sleeve, a collar rigidly connected to the outer end of said sleeve through which said piston reciprocates, a lever pivotally mounted on said base and pivotally connected to said collar, and means for actuating said lever to slide said sleeve inwardly of said bore, the lower end of said sleeve having fitting therein a ball valve cage and the lower end of said ball valve cage having connected thereto a cap having a conical outer wall providing a release valve adapted to seat upon and close said release valve seat, said cap having a central passageway extending therethrough, said ball valve cage having two passageways, one of which connects the passageway of the cap with the interior of the sleeve, a valve seat in said passageway and a ball seatable thereon and disposed between said valve seat and the cap, the other passageway in said cage having one end connecting with the interior of the sleeve and the other end of said passageway terminating laterally of said sleeve and constantly communicating with the passageway in the bore that connects with the reservoir, a seat in said last mentioned passageway and a ball seatable thereon, and means to reciprocate said piston.

11. An hydraulic jack comprising in combination a relatively shallow base having a well formed in its upper surface, said base about said well being countersunk and provided with an upstanding circular shoulder concentrically surrounding said countersunk portion, a ram cylinder fitting to the walls of said well interiorly of said countersunk portion, and a sleeve concentrically surrounding said ram cylinder and fitting to the upstanding circular shoulder, a ring-like cap closing upon the outer ends of said ram cylinder and sleeve to form a liquid-holding reservoir between the countersunk portion, the ring-like cap, the ram cylinder, and the sleeve, a ram in said ram cylinder, said base having a bore formed therein laterally of the reservoir and inclined with respect to the longitudinal axis of the ram cylinder, the

bottom of said bore being formed with a valve seat and a passageway located centrally of said seat, said base having a pair of passageways formed in its walls, one of said passageways connecting with the passageway formed centrally of the seat in the bottom of said bore, said last mentioned passageway being inclined upwardly and connecting with the well, a geometric projection of the walls of said last mentioned passageway passes above the countersunk portion of the base and above the surrounding upstanding shoulder of the base whereby said passageway may be drilled when the ram cylinder and sleeve are removed, the second of said passageways being formed in the base at an angle to said bore and connecting at its lower end with the bottom of said bore in said base and at its upper end with the reservoir, a high pressure pump cylinder slidably mounted in said bore and provided at its lower end with a valve cage, the lower portion of said valve cage carrying a conical nose, the walls of which are adapted to seat upon the walls of said valve seat formed in the bottom of said bore, said cage and nose being suitably ported and having valves therein interconnecting the first and second passages with the interior of the pump cylinder sleeve, a piston slidable in said pump cylinder sleeve, means for reciprocating said piston, and means on the base for slidably adjusting the pump cylinder sleeve with respect to the bore to permit the nose to be moved onto and away from the valve seat in the bore.

12. In an hydraulic jack having a base provided with a bore, said base having thereon a ram cylinder, a liquid reservoir associated with the base, a pump cylinder comprising a sleeve of substantially uniform cross section throughout its length and having a smooth exterior slidably in said bore of said base, a ram for the ram cylinder, a piston reciprocal in the pump cylinder sleeve, conduit means in the base interconnecting the reservoir, the pump cylinder and the ram cylinder, ported and valve means carried by the pump cylinder sleeve for transferring liquid through said conduit means from the reservoir to the pump cylinder and from the pump cylinder to the ram cylinder upon reciprocation of said piston release valve, means including a valve seat formed in the base in association with certain of said ports and including a release valve carried by said ported and valved means and shiftable with said slidable cylinder sleeve and ported valve means, and actuated means connected to the outer end of said pump cylinder sleeve at a point beyond the outer end of the bore in the base when said sleeve is in its innermost slidable position therein for sliding said sleeve in a direction parallel to its longitudinal axis and in a direction toward the valve seat and the base to close the release valve upon its seat, said actuated means including mechanism whereby on release of said actuated means the pressure below said pump cylinder will freely slide said cylindrical sleeve outwardly to release the pressure therein back into the reservoir through certain of said ports.
